UNITED STATES PATENT OFFICE.

MARGUERITE A. BUCHWALTER, OF NEW YORK, N. Y.

DESIGN FOR A FLOWERPOT OR SIMILAR ARTICLE.

Application filed June 14, 1928. Serial No. 27,123. Term of patent 7 years.

To all whom it may concern:

Be it known that I, MARGUERITE A. BUCHWALTER, a citizen of the United States, residing at New York city, county and State of New York, have invented a new, original, and ornamental Design for Flowerpots or Similar Articles, of which the following is a specification, reference being had to the accompanying drawing, forming part thereof.

The single figure is a perspective view of the flowerpot.

What I claim is:

The ornamental design for a flowerpot or similar article substantially as shown.

MARGUERITE A. BUCHWALTER.
